UNITED STATES PATENT OFFICE.

JOHN A. FALLGATTER, OF HURON, DAKOTA TERRITORY.

FIRE-ESCAPE.

SPECIFICATION forming part of Letters Patent No. 375,701, dated December 27, 1887.

Application filed June 1, 1887. Serial No. 239,975. (No model.)

To all whom it may concern:

Be it known that I, JOHN A. FALLGATTER, a citizen of the United States, residing at Huron, in the county of Beadle and Territory of Dakota, have invented certain new and useful Improvements in Fire-Escapes; and I do hereby declare the following to be a full, clear, and exact description of the invention, such as will enable others skilled in the art to which it appertains to make and use the same.

This invention relates to that class of fire-escapes which are attached to the outside of houses for the purpose of enabling persons to descend thereby from any window of the house; and the object of the invention is, first, to provide a ladder long enough to reach from the upper windows of a house to the ground, and to so hang it that it may be stored compactly against the side of the house when not in use, 2c and that it may also be supported for service far enough from the house so that persons may descend on the inner face of the ladder between it and the house, while the outer face of the ladder is free to be used by firemen in carrying up their hose, &c.; second, to so hang the ladder that it may be moved in front of any column of windows by a person on the ground, and, third, to so construct and hang the ladder that when stored away it may not be used by 30 burglars.

To this end my invention consists in the construction and combination of parts forming a fire-escape, hereinafter described and claimed, reference being had to the accompanying drawings, in which—

Figure 1 is a front elevation of a house, showing my fire-escape stored away out of service. Fig. 2 is a side elevation of the same, and Fig. 3 is a similar side elevation showing the fire-escape ready for service.

5 represents either the front or any side of a house to which the fire escape is to be secured.

6 represents a series of strong brackets permanently secured to the face of the house in any suitable manner.

7 represents the upper section of the ladder, which is hung upon a slide-bar, 8, by means of hooks 9, which may slide freely along the bar.

10 represents a series of braces rigidly secured at their upper ends to the slide-bar and

pivoted midway to the brackets upon bolts 11, and stepped at their lower ends, 12, in the same brackets 6 in such a manner that the said lower ends will swing out free of the steps 12 when 55 the slide-bar 8 is moved back to the house, as in Fig. 3.

13 represents the lower section of the ladder, which is fitted to slide endwise and extend below the upper ladder, 7, the two ladders being 60 extensibly secured together by any usual means, such as the hasps 14.

15 is a short hook, and 16 a series of staples fixed in the house beside different windows, whereby the ladder may be secured close to 65 the house when not in service, and 17 is a longer hook, whereby the ladder, when extended to the ground, may be secured in front of any window by means of the same staple 16.

When the ladder is in service, the slide-bar 70 8 stands out from the house beyond the vertical plane of the pivots 11, and the weight of the upper section of the ladder hanging thereon tends to hold the feet of the braces 10 in their steps 12, and the foot of the lower section 75 of the ladder rests on the ground. This causes the necessity for the long hook 17. When the ladder is stored against the house, as in Fig. 3, the bar 8 is between the plane of the pivots 11 and the house, and the weight of the upper 80 section of the ladder tends to hold the bar and ladder against the house, and the foot of the lower section of the ladder may rest on a ledge, 18, of the house-finish, or upon a shelf suitably fixed to the house so far above ground as to 85 be inaccessible to burglars.

19 represents a wire rope attached midway to the top of the ladder, thence passing over pulleys 20, which are secured on the slide-bar near its ends, and thence to the ground. By 90 this means a person on the ground may draw the ladder in front of any window.

21 represents pins projecting from the face of the house, over which pins the wire rope may be done up when not in use, out of reach 95 of persons on the ground, but within reach of a person at the second-story windows. The bar 8 may be moved to or from the house either by a person at an upper window taking directly hold of the ladder or by means of one 100 of the braces 10, used as a lever. The side bars of the ladder and the slide-bar should be made

of iron pipe, for sake of lightness and strength, and every part of the fire escape should be iron, for safety and durability.

Having thus fully described my invention, 5 what I claim, and desire to secure by Letters Patent, is—

1. The combination of the brackets 6, provided with the steps 12, the braces 10, pivoted midway in the said brackets and adapted to engage the steps 12, and the slide-bar 8, secured to the upper ends of the said braces, substantially as shown and described. 10

2. The combination of the brackets 6, adapted to be secured to a house, and provided with the 15 steps 12, the braces 10, pivoted in the brackets and adapted to engage the steps 12, the slide-bar 8, secured to the upper ends of the said braces, the ladder 7, provided with hooks 9, adapted to engage the slide-bar 8, the ladder 20 13, secured to the ladder 7 with a sliding fit, and the ledge 18, fixed to the house in position to support the ladders, substantially as shown and described.

3. The combination of the brackets 6, secured to a house, the braces 10, pivoted and stepped in the brackets, the slide-bar 8, secured upon the said braces, the two ladders 7 25 and 13, fitted to slide together and provided

with hooks 9, adapted to slide upon the bar 8, the staples 16, secured to the house beside windows thereof, and the short hook 15 and the long hook 17, both adapted to engage any one of the staples 16 at the proper time, substantially as shown and described. 30

4. The combination of the brackets 6, secured to a house, the braces 10, pivoted and stepped in the brackets, the slide-bar 8, secured upon the said braces, the pulleys 20, secured on the slide-bar near its ends, a ladder hung upon the slide-bar by means of hooks, 40 pins 21, projecting from the face of the house, and a wire rope, 19, secured midway to the said ladder, thence passing over the said pulleys 20 and hanging in position to be done up on the pins 21, substantially as shown and described. 45

5. The combination of the brackets 6, having steps 12, the braces 10, pivoted in said brackets, and the bar 8, supported on said braces, as and for the purpose described. 50

In testimony whereof I affix my signature in presence of two witnesses.

JOHN A. FALLGATTER.
